DOOR SEALING ARRANGEMENT

William Young, Washington, D. C.

Application June 3, 1944, Serial No. 538,670

8 Claims. (Cl. 20—69)

1

My invention relates to door sealing arrangements and its principal object is to provide metal to metal resistance to extension of fire on shipboard, either into or out of separate compartments or structure, by way of doors or hatch covers.

A primary feature of the invention consists in providing metal means adapted to resist the passage of fire from one side of a ship's door to the other which may be easily installed or applied after the door is hung or placed in position and which may be applied to the doors of most ships now in service and in production without making any modification in the structure of those doors.

Another feature of the invention consists in providing plate-like means rigidly mounted around a door or hatch for overlapping the outer edges of the door or hatch for resisting the passage of fire from one side of the door to the other.

A further feature of the invention consists in providing plate-like means which is capable of being mounted on the door frame or hatch coaming for cooperating with the outer edges of the door or hatch to resist the passage of fire.

Other features of the invention, residing in advantageous forms, combinations and relations of parts, will hereinafter appear and be pointed out in the claims.

In the drawings,

Figure 1 is a front view of a bulkhead door and frame embodying the invention, the lower part of the door being omitted to show more clearly parts on the bulkhead which are cooperable therewith.

Figure 2 is a horizontal sectional view of the door and bulkhead shown in Figure 1.

Figure 3 is an enlarged sectional view of one edge of the door and the adjoining portions of the bulkhead.

Figures 4, 5, 6, 7, 8 and 9 are views similar to Figure 3 each embodying slightly different forms of the invention.

The invention is shown in the drawings as applied to bulkheads and their associated doors but it will be apparent to those skilled in the art that the invention is not limited to use with bulkhead doors but can be used with equal effectiveness and facility with closures of any type employed on ships, for example, hatch covers.

Referring more particularly to the drawings and specifically to the embodiment of the invention shown in Figures 1, 2 and 3, 1 indicates a metal door having inturned marginal flanges 2. The door is shown, in Figures 1 and 2, pivotally con-

2

nected by suitable hinge members 3 to a bulkhead 4 and any suitable means, such as the well known pivoted dogs 5, shown in dot and dash lines in Figure 1, may be employed for locking or securing the door in closed position.

A strip of relatively flexible sealing material 6 of the desired substance is mounted on the inner face of the door adjacent the marginal flanges thereof and it is adapted to be compressed intermediate its edges by a rigid flange 7 surrounding the door opening. This sealing material can be connected to the door in any of the well known or suitable manners heretofore employed.

In the form of the invention shown in Figures 1, 2 and 3, the sealing material is connected to the door by a pair of laterally spaced oppositely arranged angle members 8 and 9, respectively. Angle 8 is spot welded or connected in any other desired manner, to the marginal flange of the door 20 while angle 9 may be similarly connected to a bar or plate-like member 10 which is secured, as by welding for example as indicated at 11, to the door adjacent the inner side edge of the sealing material. For sake of clarity, angles 8 and 9 have been omitted from Figures 1 and 2.

The rigid flange 7 which surrounds the door opening for cooperating with the sealing material is shown in Figures 1, 2 and 3 as being an integral part of the bulkhead. The locking or securing 30 dogs 5 force the door inwardly with respect to the rigid flange a sufficient distance to compress the sealing material and thereby render the door satisfactorily water-tight. The extent to which one type of sealing material may be advantageously compressed is indicated in dotted lines in Figure 3.

For resisting the passage of fire from one side of the door to the other, metal means is provided for overlapping the outer faces of the marginal flanges of the door. This means is of such construction that it can, in effect, telescope with respect to the marginal flanges of the door and thus not interfere with closing of the door and compression of the sealing material. In the form 45 of the invention illustrated in Figures 1, 2 and 3, the means for resisting the passage of fire comprises a flat structural bar 12 which is spaced from and arranged in parallel relation with the rigid flange of the bulkhead. The inner edge of this 50 bar may be secured in any suitable fashion, such as by welding as indicated at 13, and its outer end portion is adapted to be in overlapping relation with the outer face of the marginal flanges of the door when the rigid flange of the bulkhead initially engages the sealing material. The degree

of overlap between the outer portion of the bar 12 and the marginal flanges of the door will, therefore, be as great as the initial amount of overlap plus the amount the sealing material is compressed. The inner corner of the outer edge of bar 12 may be rounded, if desired.

In Figure 4 a slightly different door structure is illustrated. Here the sealing material is secured to the door at its outer edge by an integrally offset portion 15 of the marginal flange 16 and at its inner edge by an angle 17 which is connected to one flange of a larger angle 18 which may be secured to the door in any suitable manner and whose other flange is interposed between the sealing material and the door. Moreover, the rigid flange 20 which surrounds the door opening is welded, as indicated at 21, to the bulkhead instead of being formed integrally therewith.

The structural bar 22 shown in Figure 4 cooperates with the outer face of the marginal flanges 16 of the door in the same manner and for the same purpose as bar 12, in the previously described form of the invention, cooperates with the marginal flanges of the door thereof.

In the form of the invention illustrated in Figure 5 showing the same character of door construction as that of Figure 4, the means for cooperating with the outer faces of the marginal flanges 23 of the door consists of a plate member 24 which is thinner than the bars 12 and 22 of Figures 3 and 4 but to give it substantially the same rigidity as those bars against lateral deflection or bending, its outer end portion is curved as indicated at 25. It is arranged to cooperate with the marginal flanges of the door in the same manner and for the same purpose as the corresponding bars 12 and 22.

In Figure 6, the invention is shown as embodied in a door construction wherein the bounding or marginal flanges of the door are not disposed at right angles to the main body of the door. Here an integral channel-like member 26 is secured in any advantageous manner to the edge portions of the door and in order that the sealing material 27 may be retained therein without any extraneous means, either or both of the legs or flanges 28 may converge toward each other. Means 29, like the bars 12 and 22 of Figures 3 and 4, respectively, may be employed to cooperate with the outer leg of the channel in much the same fashion and for the same purpose as the bars 12 and 22 cooperate with their respective doors. However, when the outer leg of the channel is oblique with respect to the body of the door as shown, it is not possible to obtain the same degree of telescoping action as where the marginal flanges are normal to the door but all telescoping movement ordinarily required between the fire resisting member and the door can be obtained by beveling or inclining the inner face of the outer portion of the bar, as indicated at 30, to the same angle as the outer face of the inclined flange.

In the forms of the invention illustrated in Figures 7, 8 and 9, the means which overlaps the outer face of the marginal flanges of the door to resist the passage of fire is secured to the rigid flange surrounding the door opening for compressing the sealing material, instead of to the wall of the bulkhead or to the deck adjoining the hatch, as shown in the other embodiments of the invention. Mounting the fire resisting means in this manner is particularly desirable in those cases when the closed door or hatch is disposed

at such a great distance from adjoining ship structure that the use of a bar or plate, such as 12, 22, 24 and 28 in Figs. 3, 4, 5 and 6, respectively, might not seem suitable.

5 In the form of the invention illustrated in Figure 7, the door construction is the same as that illustrated in Figure 4 and the member 31 for resisting the passage of fire is a structural Z bar. The Z member is connected to the rigid flange 10 32 surrounding the opening by spot welding or otherwise securing its inner leg 33 to said flange in such position that the outer leg 34 of the Z will project outwardly into overlapping relation with the outer face of the marginal flanges 15 of the door. The outer flange is of such depth that it may telescope with the door such distance as is necessary to enable the flange to cooperate with the marginal flanges of the door in the same manner and for the same purpose as bar 12 of 15 the embodiment of the invention shown in Figure 20 3.

It will, of course, be recognized that by using a member of this character the flange which contacts with the outer face of the marginal flanges 25 of the door may be easily bent from its normal position, as indicated in Figure 7, to provide the exact clearance which will permit operation of the door and yet which will resist passage of fire from one side of the door to the other.

30 In Figure 8, the effect of a Z member is obtained by welding or otherwise suitably securing two angle bars back to back. In such construction, the leg 36 of one of the angles is secured to the rigid flange 37 surrounding the door opening in such 35 manner that the outer leg 38 of the other angle may overlap the outer face of the marginal flanges of the door and cooperate therewith in the same manner as the outer flange 34 of the Z member in Figure 7. The advantage of employing a built up Z member as in Figure 8, instead of the integral one as in Figure 7, is that the two parts of the built up Z can be so connected that the inner and outer legs thereof may be disposed in any desired spaced relationship.

45 In the form of the invention illustrated in Figure 9, the member for resisting the passage of fire is a reversely bent plate 40. This plate is connected directly to the rigid flange 41 surrounding the door opening so that the outer one of 50 the two reversely bent portions 42 opens outwardly away from the bulkhead or hatch. The outer leg 43 of this portion is adapted to overlap the outer face of the marginal flanges 44 of the door in the same manner and for the same purpose as the outer leg 34 of the Z member in Figure 7. The distance between the two free legs of a reversely bent member of this character may be easily varied, if necessary, to meet different conditions.

60 With a bar or other means here described for resisting the passage of fire from one side of the door to the other by coacting with the outside edges or bounding flanges of the door or other closure, the amount of clearance between the fire

65 resisting means and the door for best meeting operating requirements can be definitely and easily determined. Moreover after being once experimentally determined for a particular type of door, the necessary amount of clearance can be 70 easily reproduced when the fire resisting means is subsequently applied to doors of the same type by merely employing a suitable temporary means of the required thickness which will afford an actual bearing for fitting purposes against the 75 coacting edge of the door or hatch. Upon re-

removal of the temporary means, such for example as shims or even paper, the desired condition of operating clearance will then exist. It is thus seen that normal operation of the door and effective functioning of the fire resisting arrangement can be readily assured.

Furthermore, by providing a fire resisting means which overlaps the outer surface of the bounding edge or flange of the door, it will be apparent that its use will require no change or alteration in any part of the door structure. In fitting the fire resisting means to the door, this can be done when the door is in the position of closure it assumes when the sealing material thereof first engages the flange surrounding the door opening or in any other further position of closure wherever the bounding flanges are normal to the body portion of the door but when the marginal flanges are oblique to the body portion, as in Figure 6, the fitting can be properly accomplished only when the door is in tightly locked position.

Various changes in the details of door construction described and of the particular means described for connecting the various parts thereof may, of course, be made without departing from the spirit and scope of the invention defined in the appended claims.

What I claim is:

1. A sealing arrangement for closures having inturned marginal flanges comprising a strip of relatively flexible sealing material on the inside of the closure adjacent said marginal flanges, a rigid flange surrounding the opening to be closed by the closure for compressing said strip of sealing material intermediate its side edges, and a separate member immovably mounted with respect to said rigid flange capable of being fitted with respect to the closure after it is hung for overlapping the outer face of said marginal flanges when the outer end of said rigid flange initially contacts the sealing material, said member being so formed to enable the closure to move inwardly with respect thereto to compress said sealing material and being spaced in such closely contiguous relation with said marginal flanges as to resist passage of fire from one side of the closure to the other when the sealing material is compressed.

2. A sealing arrangement for closures having inturned marginal flanges comprising a strip of relatively flexible sealing material on the inside of the closure adjacent said marginal flanges, a rigid flange surrounding the opening to be closed by the closure for compressing said strip of sealing material intermediate its side edges, and a separate member immovably mounted with respect to said rigid flange capable of being fitted with respect to the closure after it is hung having a portion adapted to overlap the outer face of said marginal flanges when the outer end of the rigid flange initially contacts the sealing material, said portion being substantially parallel with said marginal flanges and being spaced in such closely contiguous relation with said marginal flanges as to resist passage of fire from one side of the closure to the other when the sealing material is compressed.

3. A sealing arrangement for closures having inturned marginal flanges comprising a strip of relatively flexible sealing material on the inside of the closure adjacent said marginal flanges, a rigid flange surrounding the opening to be closed by the closure for compressing said strip of sealing material intermediate its side edges, and

separate plate-like means immovably mounted with respect to said rigid flange and disposed in spaced relation thereto capable of being fitted with respect to the closure after it is hung for overlapping the outer face of said marginal flanges when said rigid flange initially contacts the sealing material, said means being adapted to permit the closure to telescope therewith and being in such closely contiguous relation with said marginal flanges as to resist passage of fire from one side of the closure to the other when the sealing material is compressed.

4. A sealing arrangement for closures having inturned marginal flanges comprising a strip of relatively flexible sealing material on the inside of the closure adjacent said marginal flanges, a rigid flange surrounding the opening to be closed by the closure for compressing said strip of sealing material intermediate its side edges, and a separate plate-like member capable of being fitted with respect to the closure after it is hung having its inner end mounted in spaced relation to said rigid flange and its outer portion adapted to overlap the outer face of said marginal flanges when the outer end of said rigid flange initially contacts the sealing material, said means being adapted to permit the closure to telescope therewith and being cooperable with said marginal flanges to resist passage of fire from one side of the closure to the other when the sealing material is compressed.

5. A sealing arrangement for closures having inturned marginal flanges comprising a strip of relatively flexible sealing material on the inside of the closure adjacent said marginal flanges, a rigid flange surrounding the opening to be closed by the closure for compressing said strip of sealing material intermediate its side edges, and a separate flat bar substantially parallel with said rigid flange and mounted in spaced relation thereto capable of being fitted with respect to the closure after it is hung, the outer end portion of said bar being adapted to overlap the outer face of said marginal flanges when said rigid flange initially contacts said sealing material and being arranged in such closely contiguous relation with said marginal flanges when the sealing material is compressed as to resist passage of fire from one side of the closure to the other.

6. A sealing arrangement for closures having inturned marginal flanges comprising a strip of relatively flexible sealing material on the inside of the closure adjacent said marginal flanges, a rigid flange surrounding the opening to be closed by the closure for compressing said strip of sealing material intermediate its side edges, and means capable of being fitted with respect to the closure after it is hung for resisting the passage of fire from one side of the closure to the other, said means including a member having oppositely projecting flanges one of which is secured to said rigid flange and the other of which is adapted to overlap the outer face of the marginal flanges of the closure when said rigid flange initially contacts the said sealing material, the last named flange of said means being arranged to permit inward movement of the closure and being disposed in such contiguous relation thereto when the sealing material is compressed as to resist passage of fire from one side of the closure to the other.

7. A sealing arrangement for closures having inturned marginal flanges comprising a strip of relatively flexible sealing material on the inside

of the closure adjacent said marginal flanges, a rigid flange surrounding the opening to be closed by the closure for compressing said strip of sealing material intermediate its side edges, and a Z-shaped member having oppositely projecting flanges, one of the flanges of the Z being rigidly connected to the outer side of said rigid flange and the other of said flanges thereof being adapted to overlap the outer face of the marginal flanges of the closure when said sealing material initially engages said rigid flange, the last named flange of the Z-shaped member being arranged so as to permit the closure to move inwardly with respect to said rigid flange so as to compress the sealing material and being spaced in such closely contiguous relation with said marginal flanges of the closure as to resist passage of fire from one side of the door to the other.

8. A sealing arrangement for closures having inturned marginal flanges comprising a strip of relatively flexible sealing material on the inside of the closure adjacent said marginal flanges, a rigid flange surrounding the opening to be closed by the closure for compressing said strip of sealing material intermediate its side edges, and a re-

10

15

25

versely curved member having oppositely extending flanges, one of said flanges being connected to said rigid flange and the other of said flanges being adapted to overlap the outer face of the marginal flanges of the closure in such closely contiguous relation when the closure is fully closed as to resist the passage of fire from one side of the closure to the other.
